UNITED STATES PATENT OFFICE.

MARIO BRAGALDI, OF NEW YORK, N. Y.

BOX FOR LETTERS AND OTHER ARTICLES.

SPECIFICATION forming part of Letters Patent No. 349,382, dated September 21, 1886.

Application filed September 28, 1885. Serial No. 178,399. (No model.)

To all whom it may concern:

Be it known that I, MARIO BRAGALDI, of the city and State of New York, have invented an Improvement in Boxes for Letters and other Articles, of which the following is a specification.

In Letters Patent No. 192,146, granted to me June 19, 1877, a letter-box is shown and described having two flaps at the bottom of the box, the outer one being held by a lock operated by a key, and the inner one held by bolts that are operated by a frame connected to a pouch, said frame being inserted in the base of the box after the outer flap had been opened by a key. The insertion of this frame in the base of the box caused the inner flap of the box to drop simultaneously with the opening of a flap in the top of the pouch, thereby allowing the letters in the box to drop into the pouch, and upon the withdrawal of the frame and pouch from the box both said flaps were closed and locked simultaneously.

My present invention relates to the lock mechanism of the inner flap of the letter-box, and to the flap of the letter-pouch, whereby great security is afforded against the contents of the letter-box, or of the pouch after the letters have been dropped therein, being tampered with. I make use of spring tumblers and levers upon the frame of the flap of the pouch for operating the bolts that hold said flap, and these tumblers are operated by keys supported within the base of the letter-box, which keys are brought down in line with the tumblers by levers and links actuated by projections on the pouch-frame when said frame is inserted into the base of the letter-box.

In the drawings, Figure 1 is a front elevation of the letter-box with the outer flap opened. Fig. 2 is an elevation, partly in section, of the same. Fig. 3 is a vertical transverse section of the lower part of the box at the line $x-x$, Fig. 1, with the pouch-frame partly entered within the box. Fig. 4 is a section at the line $y-y$ of Fig. 3 with the parts in the same position. Fig. 5 is a section at the line $z-z$, Fig. 4, with the parts in the position they assume after the pouch-frame has been fully entered below the box. Fig. 6 is a sectional plan at one corner of the letter-box, the inner casing of the box not being shown; and Fig. 7 is a

plan, partly in section, of the pouch-frame and parts carried by it.

The letter-box a , inner flap, b , hinged at 2, outer flap, c , hinged at 3, slides l for the flanges i' , of the pouch-frame i , flanges o and n upon the respective flaps, b and m , for connecting said flaps, so that they move together when being opened and closed, are substantially the same as shown in my aforesaid patent. The lock at c' , operated by a key inserted at d' for releasing the hook 4 , upon the flange c' of the flap c , and the dial e^2 , having numbers thereon, one of which is visible through the opening e^2 , to indicate the time of the next collection of letters, may also be of the character set forth in my said patent.

At a^3 I have shown an opening for the insertion of letters into the box a , and this opening is closed by a hinged flap, a^4 . There may be one or more openings, a^5 , in the top of the box, closed by thick glass, to enable the letter-carrier to see if there are letters in the box, and I provide an interior casing, a^6 , to the box, into which casing the letters pass as 75 dropped through the opening a^3 . The casing a^6 is larger at the bottom than at the top, so that the letters will always pass down freely. This casing is supported upon a plate, a^7 , that is riveted or otherwise secured to the lower 80 part of the box a , and in this plate there is an opening that is closed by the flap b . The flap b is kept closed by bolts p , that pass into holes in the flap b , and these bolts are upon levers q pivoted at 10 in recesses beneath the 85 plate a^7 at the sides of the box. The levers q have inclined ends 12, that are acted upon by the raised portions q^2 of the flanges i' of the pouch-frame when said pouch-frame is being passed into the base of the box, and these projections swing the lever q and withdraw the bolts p , allowing the flap b to drop. Before the lever q can be moved by the pouch-frame it is necessary to lift the spring-dog r , the free end of which is behind the incline 12 of 95 q . This is accomplished by the frame i running under the projection 17 on the dog, which lifts the dog sufficiently high for the inclined end of q to pass beneath it. (See Fig. 3.) When the pouch-frame is withdrawn, the 100 spring 11 moves the lever q , and the bolts enter the flap b and hold the same, said flap b

having been raised by the withdrawal of the frame, as hereinafter described. The means just described for locking and releasing the flap *b* are similar to those in my said patent.

- 5 The flap *m* of the pouch-frame is pivoted at 9 to the frame *i*, and said frame *i* and pouch are permanently connected together, and adapted to being inserted underneath and removed from the letter-box, and the flap *m* 10 opens inwardly, and when closed is held up by the turning-bolts *t*, each bolt being upon a stud, 18, passing through the frame *i*, and carrying a pinion, 19, that gears into a toothed segment, 20, upon the lever *m*. The lever *m* 15 is upon the pivot *m*, and carries a stud, *m*, adjacent to the notches in the spring-tumblers *m*. A case, *i*, covers the levers, tumblers, and pinions, and there are openings at *i* in the case for the passage of the keys *n*, that 20 act upon the tumblers. The keys *n* are at the lower ends of vertical studs *n*, which studs are connected at their upper ends by the bar *n*, so that they can move together, and said studs are guided by the slotted tubes *n*, 25 that are secured to the plate *a*, near the front of the letter-box.

n is a spring acting between the plate *a* and the bar *n*, to keep the keys and studs elevated, and there are openings in the plate *a* to allow 30 the keys *n* to pass down below the plate *a*.

- t* are levers pivoted at 26, and *t* are links connecting the levers *t* with the levers *t*, and the arms *t* of the latter are above pins *t* upon the studs *n*, which studs are in vertical 35 slots in the tubes *n*. When the pouch-frame *i* is passed into the box *a*, the projections *q* act upon the levers *t* slightly in advance of acting on the levers *q*, and the continued movement of *i* causes the levers *t* to act through *t*, 40 *t*, and *t*, and thereby bring down the keys *n* below the plate *a* and in line with the openings *i* in the case *i*, and as further movement is given to the pouch-frame the lever *m* and tumblers *m* come in contact with the keys 45 *n*, and said levers *m* and tumblers *m* are moved, and the pins *m* enter the slots of the tumblers *m*, swinging the levers *m*, and causing the pinions 19 and bolts *t* to receive about a quarter-rotation and release the flap *m*. 50 During this operation the flap *b* had been released from the bolts *p*, as before explained, and the flaps *b* and *m* dropped simultaneously, being connected by the flanges *n* and *o*, and all letters or packages upon the flap *b* 55 passed into the pouch *h* by the swinging down of the flaps *b* and *m*. When the pouch-frame is being withdrawn, the keys *n* are raised by the spring *n* as soon as the pouch-frame has reached the position shown in Fig. 3, and 60 the parts assume the position shown in that figure, and during the withdrawal of said pouch-frame the flaps *b* and *m* are swung up by the flanges *n* and *o*, and both locked simul-

taneously before the pouch-frame is drawn out of the box *a*. 65

I have shown but two tumblers, *m*, for each key; but this number may be increased, or only one used, these tumblers being thin and lying close to each other.

Sometimes it is desirable for the letter-carrier to agitate the contents of the letter-box or of the pouch, so as to cause the mail-matter to pass down from the box into the pouch. I provide for the carrier doing this, and at the same time prevent direct access to the mail-matter by applying a glove or mitt, *g*, that is of a size to receive the hand freely, the said glove or mitt being within the pouch, and the wrist portion attached to the pouch, as shown, so that the hand can be inserted into this mitt 80 and thrust up into the box, or used to spread the mail-matter inside the pouch.

This box and its appliances are available for receiving letters or packages, or railway tickets or coupons, or for money or payments of any kind, and for the removal into the pouch of all such articles. 85

I claim as my invention—

1. The combination, with the letter-box *a*, of the keys *n*, fitted to slide vertically in the bottom plate of the box, a spring for lifting said keys, levers *t*, having their lower ends in the slideways of the box, the levers *t*, each connected at one end with a key, *n*, the links *t* connecting the levers *t* and *t*, the pouch, and the pouch-frame adapted to slide in the lower part of the letter-box, and having projections *q* to act upon the levers *t*, the flap *m* hinged to the pouch-frame, the turning-bolts *t*, for holding up said flap, and the tumblers *m* and pinions 19, for operating the turning-bolts *t*, substantially as and for the purposes specified. 90

2. The combination, with the letter-box having a hinged flap at the lower portion, of keys fitted to slide vertically in the bottom plate of the box, the pouch-frame, a hinged flap to the same, tumblers upon the pouch-frame, turning-bolts for holding up the flap, and levers arranged, substantially as set forth, to bring down the keys and operate upon the tumblers, 105 and release the bolts that hold the flap of the pouch when its frame is inserted in the base of the box, substantially as specified. 110

3. The combination, with the letter-box *a* and the flap at the bottom thereof, of a movable pouch, and a frame for the same, and a glove forming part of the pouch to allow for agitating the mail-matter, substantially as set forth. 115

Signed by me this 4th day of August, A. D. 120 1885.

M. BRAGALDI.
